UNITED STATES PATENT OFFICE

WALTER K. QUEEN, OF NEEDHAM HEIGHTS, MASSACHUSETTS

METHOD OF MAKING ROD PACKING

Application filed November 23, 1931. Serial No. 576,728.

It has been found that the packing ring of my United States Letters Patent 1,716,977, June 11, 1929, although well adapted for its intended purpose, as shown by an extensive 5 public use, is subject to a certain limitation, namely, that when the piston rod is removed for repairs thereto, or to the piston attached thereto, the packing is destroyed because the adhesive which retains the spirally-wound 10 strip of asbestos in shape until it is placed in the stuffing box is dissipated by the heat to which it is subjected.

It is therefore the object of the present invention to provide a method of making a 15 packing ring which has all the advantages of the ring set forth in said Letters Patent, and will retain its shape when removed from the stuffing box after a period of use as, for example, when it becomes necessary for any 20 reason to remove the rod packed by said ring. To this end therefore my invention contemplates the use of a single homogeneous, relatively-thick strip of packing material such as woven fabric first arranged in cylindrical 25 form with the ends thereof abutting (as distinguished from the cylinder formed by a plurality of adhesively-secured turns of the relatively thin fabric strip described in said Letters Patent) and the compression of the 30 same into an annulus having an outer convex conical surface and an inner concave conical surface with a slit through the wall thereof.

My invention will be described by reference to the accompanying drawing which is to be taken as illustrative and not restrictive. In said drawing,—

Figure 1 is a plan view of a relatively thick strip of packing material, for example, 40 woven fabric such as asbestos cotton wool and the like, with or without wire insertion;

Fig. 2 is a transverse section taken on the line 2—2 of Fig. 1;

Fig. 3 is a vertical section of a cylindrical 45 ring formed by the fabric strip shown in Fig. 1;

Fig. 4 is a section, certain parts being shown in elevation, of a die whereby the cylindrical ring shown in Fig. 2 is converted 50 into an annulus having an outer convex coni-

cal surface and an inner concave conical surface;

Fig. 5 is an elevation of the completed packing ring constructed in accordance with the present invention.

55

In the particular drawing selected to illustrate the apparatus employed for practicing my method, 10 is a single, coherent, homogeneous, relatively-thick strip of packing material such as woven fabric, for example, 60 woven asbestos, which may be provided with wire insertion, as indicated at 11. The said strip of woven fabric is much thicker than the relatively-thin helically-wound strips described in my prior patent, the thickness 65 in fact being substantially equal to that of the wall of the cylinder formed by a number of spiral winds of said relatively-thin strip shown in Fig. 6 of said patent.

The ends 12 of the fabric strip preferably 70 are inclined to the long sides thereof, although they may be at right angles thereto. The fabric strip is arranged in cylindrical form, as indicated in Fig. 3, with the ends thereof abutting, and is then placed in a die 75 plate 13 having a cone-shaped depression and compressed by the die member 14 having a conical portion corresponding with the cone-shaped depression of the die plate.

As the result of such compression there is 80 formed an annulus having an outer convex conical surface 15 and an inner concave conical surface 16, the said surfaces preferably being parallel and uniting the concentric cylindrical working edges 17, 18 which, when 85 the packing ring is in use, are in contact, respectively, with the rod to be packed and the inner periphery of the stuffing box. As indicated in Fig. 5, the wall of the annulus is 90 slit, and where the ends of the strip 10 are inclined to the length thereof, such slit will be angularly related with respect to a generatrix of the conical surfaces of the finished packing ring.

The packing ring formed in accordance 95 with the present invention is used in precisely the same manner set forth in my prior patent and is self-setting because the pressure against which the rod is to be packed acts 100 on the forward portion of the working edge

37. and forces the same into contact with the rod.

It has been found in practice that a packing ring constructed in the manner herein set forth has all the advantages of the ring described in my prior patent, and the additional advantage that it is not rendered unfit for use by the removal of the piston rod.

Having thus described an illustrative embodiment of my invention and means whereby my method may be realized in practice, without however limiting myself thereto, what I claim and desire to secure by Letters Patent is:

25. 1. The method of making a slitted frusto-conical packing-ring which consists in disposing a single, homogeneous, relatively-thick strip of woven fabric in cylindrical form with the ends thereof abutting and then dieing the same into a coherent slitted frusto-conical annulus.
2. The method of making a slitted frusto-conical packing-ring which consists in cutting the ends of a single, homogeneous, relatively-thick strip of woven fabric each at the same angle to the length thereof, disposing said strip in cylindrical form with the ends thereof abutting, and dieing the same into a coherent slitted frusto-conical annulus.
30. 3. In testimony whereof, I have hereunto subscribed my name this 20th day of November, 1931.

WALTER K. QUEEN.
